RAILWAY TRAFFIC CONTROLLING APPARATUS

Arthur E. Dodd, Edgewood, and James E. McMahon, Jr., Penn Township, Allegheny County, Pa., assignors to Westinghouse Air Brake Company, Wilmerding, Pa., a corporation of Pennsylvania

Application December 22, 1953, Serial No. 399,653

6 Claims. (Cl. 246—3)

Our invention relates to railway traffic controlling apparatus and in particular to apparatus for remotely controlling a railway wayside signal and for supplying indications to the control location of the condition of the remotely controlled signal and of traffic conditions in approach to that signal.

In systems for controlling movements of trains or vehicles over a stretch of railway track, it is often desirable to manually control a railway signal from a remote control location. When this is the case, it is also desirable for the operator at the remote control location to be aware of the condition of the remotely controlled signal and also to be informed of the traffic conditions in approach to that signal so that he can take proper action in accordance with his information. Such arrangements are often used on stretches of track which are in approach to railway interlocking plants where many switching movements may be made and traffic may be quite heavy. In such a situation a remotely controlled signal called a holding signal is controlled from the control tower which also controls the interlocking plant. Holding signals are employed so that traffic approaching the interlocking will be under control of the interlocking operator in order that the operator will have complete control over traffic approaching as well as moving through the interlocking plant.

It is an object of our invention to provide railway traffic controlling apparatus requiring only two line wires for remotely controlling a railway signal.

Another object of our invention is to provide railway traffic controlling apparatus requiring only two line wires for remotely controlling a railway signal and for providing indications at the control location of the signal condition and of traffic conditions in approach to the signal.

A further object of our invention is to provide in railway traffic controlling apparatus for remotely controlling a railway signal and for providing means for indicating at the remote control point the signal condition and the traffic condition in approach to the signal a line circuit which may be energized from either end and which may further be polarized at one end in order to effect both the control and indication functions.

According to our invention, we provide a control device such as a railway signal located adjacent a stretch of railway track. We further provide a first control relay and a signal control relay at the location of the device. At a remote control location we provide a first and a second indication relay and a control lever. A pair of control conductors extend between the two locations. Means controlled in part by the lever are provided for at times supplying energy from the device location to the control location through the winding of the first control relay to the first and second indication relays over the control conductors so that either the first control relay and the first indication relay or the first control relay and the second indication relay will be picked up. We further provide means controlled in part by the lever for at other times supplying energy to the

first indication relay and the signal control relay from the control location over the control conductors. At the location of the device, means controlled by the signal control relay are provided for controlling the device.

5 At the control location we provide indication means for indicating the condition of the control device and of traffic conditions in advance of the control device controlled by the first and second indication relays and the lever.

10 Other objects of our invention will become apparent hereinafter as the characteristic features of construction and mode of operation of our novel railway traffic controlling apparatus are described in detail.

The single accompanying drawing is a diagrammatic 15 view of railway traffic controlling apparatus embodying our invention for the remote control of a railway signal and for providing at the remote control location indications of the signal condition and traffic conditions in approach to the signal.

20 Referring now to the drawing, a stretch of railway track made up of the track rails 1 and 2 is divided into a plurality of insulated track sections 6T, 7T, 8T and 9T by insulated joints 3 in the rails. Track sections 7T, 25 8T and 9T are each provided with a track circuit including a track battery designated by the reference character TB with a prefix corresponding to the number of the associated track section and a track relay designated by the reference character TR with a prefix corresponding to the number of the associated track section. Traffic normally moves through the stretch in the direction indicated by the arrow, that is, from left to right. A holding signal 7S is provided at the entrance end of section 30 7T. Located at this signal location are an approach relay 7AR, a first control relay 7NLPR, a repeater relay 7NLPPR, a second control relay 7NLPR, a signal control relay 7HR, a signal control repeater relay 7HPR, a stick relay 7ASR, a time element relay 7TER, and a traffic controlled relay 7HDR.

Relay 7HR is provided with two windings 4 and 5. 40 Winding 4 has a relatively high resistance and winding 5 has a relatively low resistance.

Time element relay 7TER is of the type having a normally open front contact *a* and a normally closed checking contact *b*. When relay 7TER becomes energized checking contact *b* will immediately become open but front contact *a* will not become closed until relay 7TER has been energized for a predetermined time interval.

50 Relay 7HDR is a polarized relay having a neutral contact *a* which is picked up whenever relay 7HDR is energized, and a polar contact *b* which assumes a position corresponding to the direction of current flow through the relay winding and which will remain in its last operated position until current flows through the winding of the relay in the opposite direction.

55 Disposed at a remote control location, here shown as adjacent a signal 6S, are a traffic control lever K having a normal or N position, two indicating positions A and B and a reverse or R position. Associated with lever K are a plurality of contacts 6 through 11, here shown as circles with letters corresponding to the lever positions in which the contacts will be closed. For example, contacts 8 and 9 will be closed in the N position, the B position or in any position intermediate these two positions.

Also disposed at the control location are an approach 60 indication relay 7APR, a signal indication relay 7RGPR, a repeater relay 7RGAPR, a stick relay 7APSR, a signal repeater relay 6HSP; a lever lock comprising the winding of lever lock LL, a pawl LD and a lever quadrant LQ; a signal indication lamp L1 and an approach indication lamp L2.

65 Relays 7APR and 7RGPR are of the type which will pick up only when current is flowing through their wind-

ings in a particular direction and will be released at all other times. As shown in the drawing, relays 7APR and 7RGPR will pick up only when current flows through their windings in the direction indicated by the arrow. Such relays are commonly referred to as biased relays and will be so referred to hereinafter in this description. Furthermore, relay 7APR is of the type which, when picked up, will release upon a relatively small predetermined reduction in its normal operating current. Such relays are commonly referred to as marginal relays. Accordingly, relay 7APR will be referred to hereinafter as a biased marginal relay. The control circuits for relay 6HSR are not shown in the drawing since they are conventional and form no part of our invention. Suffice it to say, relay 6HSR will be energized when signal 6S displays other than its stop or red aspect. Lever quadrant LQ is suitably connected to lever K and will be moved to predetermined positions shown in the drawing corresponding to the lever positions. The lever locking means is so arranged that pawl LD will not interfere with the movement of lever quadrant LQ and lever K from their N to their R position but functions to prevent the movement of lever K and quadrant Q from their R position past their B position unless the winding of lever lock LL is energized to lift pawl LD out of the notch in lever quadrant LQ.

Operating energy at the signal location 7S is supplied by a battery WB having a positive terminal WX and a negative terminal WO. Energy at the control location is supplied by a battery EB having a positive terminal EX and a negative terminal EO. It will be obvious that other sources of energy may be substituted for batteries WB and EB in this control arrangement.

The apparatus as shown in the drawing is in its normal condition, that is, there is no train or vehicle in the stretch of track and lever K is in its normal or N position. All the track relays are energized so that their armatures are picked up. With track relays 8TR and 9TR energized, an energizing circuit for relay 7AR passing from positive terminal WX of battery WB, over front contact *a* of relay 9TR, front contact *a* of relay 8TR, the winding of relay 7AR, front contact *b* of relay 8TR and front contact *b* of relay 9TR to negative terminal WO of battery WB is closed. For reasons which will become apparent as this description proceeds, the energizing circuit for relay 7HR, which will be traced subsequently, is open and, accordingly, relay 7HR is released. It will be clear that with relay 7HR released, relay 7HPR will also be released. With relay 7HPR released, an obvious circuit including back contact *c* of relay 7HPR will be closed for supplying energy to the red lamp R of signal 7S. This lamp will therefore be lighted so that signal 7S will be displaying its red or stop aspect. A stick circuit for relay 7ASR passing from positive terminal WX of battery WB, over back contact *b* of relay 7HPR, front contact *a* of relay 7ASR and the winding of relay 7ASR to negative terminal WO of battery WB is also closed. With relay 7ASR energized, relay 7TER will be deenergized because its energizing circuit, which will be traced subsequently, is open at back contact *a* of relay 7ASR.

Furthermore, with relay 7ASR energized, a circuit will be established passing from positive terminal WX of battery WB, over front contact *b* of relay 7ASR, the winding of relay 7NLPR, front contact *a* of relay 7AR, front contact *a* of relay 7NLPPR, line wire 15, the winding of relay 7APR from left to right, contact 7 of lever K, the winding of relay 7RGPR from left to right, contact 8 of lever K, line wire 16, front contact *b* of relay 7AR to negative terminal WO of battery WB. It will be seen that the circuit just traced includes front contacts *a* and *b* of relay 7NLPPR which is energized over a front contact *a* of relay 7NLPR. The manner in which relay 7NLPPR initially becomes energized to cause relay 7NLPPR to be energized under these conditions will be made clear as the description proceeds. With current flowing through the windings of relay 7APR,

5 and 7RGPR in the direction described, relay 7APR will be released and relay 7RGPR will be picked up. With relay 7RGPR picked up a circuit is established passing from positive terminal EX of battery EB, over front contact *a* of relay 7RGPR, contact 9 of lever K and the winding of relay 7RGAPR to negative terminal EO of battery EB. Accordingly, relay 7RGAPR is picked up and a circuit is established for energizing indicating lamp L1, which lamp when lighted, indicates that signal 7S is displaying its red or stop aspect. The energizing circuit for lamp L1 may be traced from positive terminal EX of battery EB, over front contact *a* of relay 7RGAPR and the filament of lamp L1 to negative terminal EO of battery EB.

10 As was stated earlier in this description, relay 6HSR is controlled by signal 6S in such a manner that it will be energized and picked up except when relay 6S is displaying its stop aspect. With the stretch of track in advance of signal 6S vacant, signal 6S will be displaying its proceed or green aspect and, accordingly, relay 6HSR will be picked up. With relay 6HSR picked up a circuit is established for supplying energy to relay 7HDR which circuit may be traced from positive terminal EX of battery EB, over front contact *a* of relay 6HSR, front contact *a* of relay 7TR, the winding of relay 7HDR from right to left, front contact *b* of relay 7TR and front contact *b* of relay 6HSR to negative terminal EO of battery EB. With relay 7HDR supplied with current flowing through its winding from right to left, its neutral contact *a* will be picked up and its polar contact *b* will be in its left-hand position. This will have no immediate effect on the circuit arrangement.

15 Having described the apparatus in its normal condition, let it now be assumed that a train enters section 9T and commences to travel through the stretch in the normal direction. Upon the train entering section 9T its wheels and axles will shunt relay 9TR causing that relay to release and open the previously traced energizing circuit for relay 7AR. Accordingly, relay 7AR will release and thereby reverse the polarity of the energy being supplied to the line circuit including line wires 15 and 16 and thereby reverse the direction of the flow of current through the windings of relays 7APR and 7RGPR. The energizing circuit for these relays may now be traced from positive terminal WX of battery WB, over front contact *b* of relay 7ASR, the winding of relay 7NLPR, back contact *b* of relay 7AR, front contact *b* of relay 7NLPPR, line wire 16, contact 8 of lever K, the winding of relay 7RGPR from right to left, contact 7 of lever K, the winding of relay 7APR from right to left, line wire 15, front contact *a* of relay 7NLPPR and back contact *a* of relay 7AR to negative terminal WO of battery WB. It will be seen that after the pole change relay 7NLPR will be energized over the energizing circuit which has just been traced and will maintain its contact *a* closed. Therefore, its repeater relay 7NLPPR will also remain energized as just described. With relay 7NLPPR remaining energized, relays 7HR and 7HPR will remain deenergized and signal 7S will continue to display its stop or red aspect.

20 With the reversal of the polarity of the current flowing through the windings of relays 7APR and 7RGPR, relay 7RGPR will release and relay 7APR will pick up. During the time that these relays are transferring their contacts, relay 7RGAPR will be deenergized but due to its slow release characteristic, it will not release and prior to the expiration of its slow release time, relay 7APR will close its front contact *a* and establish a second energizing circuit for relay 7RGAPR passing from positive terminal EX of battery EB, over front contact *a* of relay 7APR, contact 9, and the winding of relay 7RGAPR to negative terminal EO of battery EB. Accordingly, relay 7RGAPR will remain picked up at this time. With relay 7RGAPR remaining picked up the previously traced energizing circuit for lamp L1 will

back contact *a* of relay 6HSR to negative terminal EO of battery EB. Accordingly, neutral contact *a* of relay 7HDR will pick up and polar contact *b* of relay 7HDR will move to its right-hand position. With relay 7HDR in this condition a circuit passing from positive terminal WX of battery WB, over front contact *c* of relay 7HPR, front contact *a* of relay 7HDR, right-hand contact *b* of relay 7HDR and the yellow lamp Y of signal 7S to negative terminal WO of battery WB will become established and signal 7S will display its approach aspect.

When the train or vehicle vacates section 6T and occupies the section immediately in advance of section 6T, signal 6S will commence displaying its approach aspect and relay 6HSR will pick up to thereby reverse the polarity of the circuit energizing relay 7HDR. Therefore, front contact *a* of relay 7HDR will remain closed but its polar contact *b* will move to its left-hand position. With relay 7HDR in this condition the previously traced circuit for energizing green lamp G of signal 7S will be reestablished and signal 7S will display its proceed aspect.

With lever K in its reverse or R position it is obvious that the signal 7S will now operate in a manner substantially the same as a conventional automatic signal. This is a particularly desirable feature of our arrangement since the lever may be maintained in the reverse position to allow a number of trains to move along the stretch in the normal direction without requiring the attention of the operator. However, when it is desired to restore signal 7S to stop, lever K will be moved to its B position, to which it can be moved without reenergizing the winding of lever lock LL. With lever K in its B position the previously traced energizing circuit for the windings of relay 7HR will become open at contacts 6 and 10 and relay 7HR will release. Upon relay 7HR releasing the previously traced energizing circuit for relay 7HPR will become open and that relay will also release. With relay 7HPR released, the previously traced first energizing circuit for red lamp R of signal 7S will become reestablished and signal 7S will therefore display its stop aspect. With relay 7HPR released and relay 7NLPPR already released, both branches of the energizing circuit for relay 7NLPZR will become open and relay 7NLPZR will release. Upon the release of relay 7NLPZR, an energizing circuit will be established for relay 7ASR which circuit may be traced from positive terminal WX of battery WB, over back contact *b* of relay 7HPR, back contact *b* of relay 7NLPZR, front contact *d* of relay 7AR, and the winding of relay 7ASR to negative terminal WO of battery WB. It will be apparent that if a train were approaching signal 7S, relay 7AR would be released and relay 7ASR could not be reenergized, thus preventing the arrangement from being reset to its normal condition. Upon relay 7ASR picking up it will reestablish its previously traced stick circuit including back contact *b* of relay 7HPR and front contact *a* of relay 7ASR. Therefore, relay 7ASR will remain energized regardless of the condition of relay 7NLPZR.

With relay 7ASR now picked up, a circuit will be established passing from positive terminal WX of battery WB, over front contact *b* of relay 7ASR, the winding of relay 7NLPR, and back contact *a* of relay 7NLPZR to negative terminal WO of battery WB. Therefore, relay 7NLPR will pick up and reenergize its repeater relay 7NLPPR over its obvious energizing circuit. With relay 7NLPPR picked up it will be seen that energy will once more be supplied to the windings of relays 7APR and 7RGPR over the previously traced line circuit which extends from positive terminal WX of battery WB over front contact *b* of relay 7ASR, the winding of relay 7NLPR, front contact *a* of relay 7AR, front contact *a* of relay 7NLPPR, line wire 15, the winding of relay 7APR from left to right, contact 7, the winding of relay 7RGPR from left to right, contact 8, line wire 16, front contact *b* of relay 7NLPPR and front contact *b*

of relay 7AR to negative terminal WO of battery WB. Upon relay 7NLPPR picking up an energizing circuit for relay 7NLPZR including front contact *c* of relay 7NLPPR will be reestablished and relay 7NLPZR will again become energized. With relay 7NLPZR picked up, the original pickup circuit for relay 7NLPR will become open at back contact *a* of relay 7NLPZR but relay 7NLPR will remain energized over the line circuit which has just been retraced. Furthermore, with relay 7NLPZR picked up, the energizing circuit for relay 7ASR will become open at back contact *b* of relay 7NLPZR but relay 7ASR will remain energized over its previously traced stick circuit.

With current flowing through the windings of relays 7APR and 7RGPR as just described, relay 7RGPR will pick up but relay 7APR will remain released. Upon relay 7RGPR picking up the circuit including front contact *a* of relay 7RGPR and contact 9 will become reestablished for supplying energy to relay 7RGAPR and accordingly, that relay will pick up. Upon relay 7RGAPR picking up, the previously traced energizing circuit for signal indication lamp L1 will become reestablished and that lamp will become relighted, thereby indicating that signal 7S is displaying its stop aspect. Furthermore, with relay 7RGAPR picked up, the winding of lever lock LL will become energized over its energizing circuit passing from positive terminal EX of battery EB, over front contact *d* of relay 7RGAPR, contact 11 and the winding of lever lock LL to negative terminal EO of battery EB. Accordingly, pawl LD will be picked up out of the notch of lever quadrant LQ and lever K can therefore be returned to its normal position thus restoring the apparatus to its normal condition.

It will be clear that upon the train clearing signal 7S lever K could be moved to its B position and as the train progresses through the remaining sections and finally vacates section 6T, the arrangement will clear up as just described at which time lever K can be thrown to its full normal or N position to hold signal 7S at stop until it is again desired to allow a train to move past that signal.

Another feature in the apparatus shown in the drawing is an approach locking feature. Because this feature is conventional, it will not be described in detail. Suffice it to say that while a train is approaching signal 7S which at the time is displaying a clear or green aspect, if the lever operator attempts to move lever K to its full normal or N position, he will be unable to do so since the winding of lever lock LL will be deenergized. The lever can be moved to its B position but it can not move any further. With lever K in its B position, as was previously described, the energizing circuit for the windings of relay 7HR will become open at contacts 6 and 10 of lever K and relay 7HR will release its contacts *a* and *b* opening the energizing circuit for relay 7HPR. Relay 7HPR, therefore, will release its contacts and at its contact *c* will close the circuit for energizing the red lamp R of signal 7S and at its contact *b* will complete an energizing circuit for relay 7TER which may be traced from terminal WX of battery WB, through the back point of contact *b* of relay 7HPR, the back point of contact *a* of relay 7ASR and the winding of relay 7TER to terminal WO of battery WB. Signal 7S will commence displaying its stop aspect but lever K will remain locked against further movement toward its N position. This condition will persist until relay 7TER closes its front contact *a* to reenergize relay 7ASR which, when it picks up, will close the line circuit including front contact *b* of relay 7ASR to supply energy to relay 7APR and thereby cause relay 7APR to pick up. With relay 7APR picked up, relay 7RGAPR will pick up and energize the winding of lever lock LL. It will be seen, therefore, that lever lock LL will not be energized until relay 7TER is energized for a predetermined time interval. Accordingly, through the use of conventional interlocking means, traffic control levers which control signals (not shown) govern-

remain closed and that lamp **L1** will continue to indicate that signal **7S** is displaying its stop aspect. Furthermore, with relay **7APR** now picked up an obvious energizing circuit including front contact **b** of relay **7APR** will be established for energizing relay **7APSR**. Accordingly, relay **7APSR** will pick up and establish a stick circuit for maintaining it in its energized condition which stick circuit may be traced from positive terminal **EX** of battery **EB**, over back contact **a** of relay **7RGPR**, front contact **a** of relay **7RGAPR**, front contact **a** of relay **7APSR** and the winding of relay **7APSR** to negative terminal **EO** of battery **EB**. With relay **7APSR** picked up an obvious circuit including front contact **b** of relay **7APSR** will be established for energizing lamp **L2** thereby indicating to the operator at the control location that a train or vehicle is approaching signal **7S**. It will be obvious that relays **6HSR** and **7HDR** will remain in the condition they were in when the system was described in its normal condition.

Upon the train or vehicle entering section **8T**, the wheels and axles of the train will shunt relay **8TR** thereby maintaining relay **7AR** deenergized. There will be no other change in the circuits and, accordingly, while the train or vehicle occupies section **8T** the system will remain in the condition it assumed when the train entered section **9T**. Therefore, as the train reaches signal **7S** it will come to a stop.

If the operator at the control location decides to clear signal **7S** so that the train may proceed along the stretch, the operator will operate lever **K** to its reverse or **R** position thereby opening the contacts associated with the lever which are not closed in the **R** position. Accordingly, at this time, the only contacts associated with lever **K** which will be closed are contacts **6** and **10**. For obvious reasons, it will be seen that with contact **11** now open, lever lock **LL** will be deenergized. Accordingly, pawl **LD** will drop into the notch in lever quadrant **LQ** and prevent lever **K** from being moved beyond its **B** position. With contact **9** of lever **K** now open the previously traced energizing circuit for relay **7RGAPR** will become open and relay **7RGAPR** will release after the expiration of its slow release time interval. Accordingly, the energizing circuit for lamp **L1** will become open and lamp **L1** will become dark. Furthermore, the previously traced energizing circuit for supply energy to the windings of relays **7NLPR**, **7APR** and **7RGPR** connected in series will now become open at contacts **7** and **8** and, accordingly, these relays will all release. With relay **7APR** released, the energizing circuit for relay **7APSR** will become open but that relay will remain picked up because of its slow release characteristic. It should be noted that prior to relay **7APSR** releasing, relay **7APR** will become reenergized by means to be described below to reestablish the energizing circuit for relay **7APSR**. Accordingly, lamp **L2** will remain steadily lighted at this time.

Upon relay **7NLPR** releasing, the energizing circuit for relay **7NLPPR** will become open at front contact **a** of relay **7NLPR** and relay **7NLPPR** will release to thereby open its front contacts **a**, **b** and **c** and close its back contacts **a** and **b**. Therefore, an energizing circuit will become established for supplying energy to low resistance winding **5** of relay **7HR** connected in series with relay **7APR** which circuit may be traced from positive terminal **EX** of battery **EB**, over back contact **b** of relay **7RGAPR**, contact **6**, the winding of relay **7APR** from right to left, wire **15**, back contact **a** of relay **7NLPPR**, back contact **c** of relay **7AR**, winding **5** of relay **7HR**, back contact **b** of relay **7NLPPR**, wire **16**, contact **10** and back contact **c** of relay **7RGAPR** to negative terminal **EO** of battery **EB**. It will be clear that at this time, high resistance winding **4** of relay **7HR** will be short circuited by back contact **c** of relay **7AR**. With relay **7APR** energized in series with low resistance winding **5** of relay **7HR**, these relays will both pick up. Upon relay

7HR picking up, an energizing circuit will be established for supplying energy to repeater relay **7HPR** passing from positive terminal **WX** of battery **WB**, over checking contact **b** of relay **7TER**, front contact **a** of relay **7HR**, the winding of relay **7HPR** and front contact **b** of relay **7HR** to negative terminal **WO** of battery **WB**. Accordingly, relay **7HPR** will pick up and open the previously traced stick circuit for relay **7ASR** thereby causing relay **7ASR** to release. Furthermore, upon the release of relay **7NLPPR**, the energizing circuit for relay **7NLPPR** will become open at front contact **c** of relay **7NLPPR** but relay **7NLPPR** will continue to be energized over a second energizing circuit including front contact **a** of relay **7HPR**. Relay **7HDR** will remain energized at this time in the manner previously described and with relay **7HPR** now picked up, a circuit will be established for supplying energy to the green lamp **G** of signal **7S** which circuit may be traced from positive terminal **WX** of battery **WB**, over front contact **c** of relay **7HPR**, front contact **a** of relay **7HDR**, left-hand contact **b** of relay **7HDR** and green lamp **G** of signal **7S** to negative terminal **WO** of battery **WB**. Therefore, signal **7S** will display its green or proceed aspect and the train or vehicle may proceed over the stretch past signal **7S**.

Upon the train moving past signal **7S**, its wheels and axles will shunt track relay **7TR** and cause that relay to release, thereby opening the energizing circuit for relay **7HDR** to cause that relay to release. Accordingly, the circuit for lighting green lamp **G** of signal **7S** will be open and a second energizing circuit for red lamp **R** of signal **7S** will be established which circuit may be traced from positive terminal **WX** of battery **WB**, over front contact **c** of relay **7HPR**, back contact **a** of relay **7HDR** and the red lamp **R** of signal **7S** to negative terminal **WO** of battery **WB**. It will be obvious that the remainder of the apparatus will remain in the condition last described until the train vacates section **8T** and occupies only section **7T**.

When the train does vacate section **8T**, the previously traced energizing circuit for relay **7AR** will become re-established and relay **7AR** will pick up. Upon relay **7AR** picking up, a circuit will be established for supplying energy to relay **7APR** and the high resistance winding **4** of relay **7HR** connected in series with the low resistance winding **5** of relay **7HR**, which circuit may be traced from positive terminal **EX** of battery **EB**, over back contact **b** of relay **7RGAPR**, contact **6**, the winding of relay **7APR**, wire **15**, back contact **a** of relay **7NLPPR**, resistor **R**, winding **4** of relay **7HR**, winding **5** of relay **7HR**, back contact **b** of relay **7NLPPR**, wire **16**, contact **10** and back contact **c** of relay **7RGAPR** to negative terminal **EO** of battery **EB**. With this circuit established the current flow through the winding of relay **7APR** will be sufficiently reduced to cause that relay to release due to its marginal characteristic. Upon relay **7APR** releasing, relay **7APSR** will also release after the expiration of its slow release time interval and thereby open the obvious energizing circuit for approach indication lamp **L2** which will go dark, thereby indicating that a train or vehicle is no longer approaching the signal **7S**. As long as the train occupies section **7T** the above described condition will be maintained.

However, upon the train entering section **6T** signal **6S** will commence displaying its red aspect and relay **6HSR** will release. Upon relay **6HSR** releasing there will be no immediate change in the apparatus since the circuit which includes front contacts **a** and **b** of relay **6HSR** is already open at front contacts **a** and **b** of relay **7TR**. However, upon the train vacating section **7T** and occupying only section **6T** relay **7TR** will pick up and establish a circuit for energizing relay **7HDR** from left to right which circuit may be traced from positive terminal **EX** of battery **EB**, over back contact **b** of relay **6HSR**, front contact **b** of relay **7TR**, the winding of relay **7HDR** from left to right, front contact **a** of relay **7TR** and

ing traffic movements in the opposite direction cannot be operated until after the expiration of the predetermined time interval. In this manner, the train approaching signal 7S will be given sufficient time to comply with the stop aspect of signal 7S or, if the train should overrun that signal, to cause relay 7TR to release to thereby continue to prevent, through well known interlocking means, the signals governing traffic movements in the reverse direction from clearing to a proceed or an approach aspect.

Although we have herein shown and described only one form of railway traffic controlling apparatus embodying our invention, it will be understood that various changes and modifications may be made therein within the scope of the appended claims without departing from the spirit and scope of our invention.

Having thus described our invention, what we claim is:

1. In an arrangement for controlling from a remote control location a device governing traffic movements over a stretch of railway track and for providing indications at said remote control location of the condition of said device and of traffic conditions in approach to said device, a first control relay, a signal control relay having low and high resistance energizing paths, pole changing means responsive to traffic conditions in approach to said device, said first control relay, said signal control relay and said pole changing means being situated at the location of said device; a biased marginal relay, a second biased relay and a traffic control lever at said control location; a pair of control conductors extending between said two locations; means controlled in part by said lever and said pole changing means for at times supplying energy from the location of said device to said first control relay, said biased marginal relay and said second biased relay over said control conductors; said last mentioned means being effective to control the application of energy so that either said first control relay and said biased marginal relay or said first control relay and said second biased relay will be picked up, means controlled by said lever and said first control relay for at other times supplying energy from said control location to said biased marginal relay and said signal control relay over said control conductors; said last mentioned means being effective when the stretch in approach to said device is occupied to cause energy to be supplied to a circuit including the low resistance energizing path for said signal control relay so that both said signal control relay and said biased marginal relay will be picked up but operative when said stretch in approach to said device is unoccupied to cause energy to be supplied to a circuit including the high resistance energizing path for said signal control relay so that the signal control relay will be picked up but said biased marginal relay will be released; means controlled by said signal control relay for governing the operation of said device, approach indication means at said control location controlled by said biased marginal relay, and means for indicating the condition of said device; said biased marginal relay, said second biased relay and said lever each partially controlling said last means.

2. In an arrangement for controlling from a remote control location a device governing traffic movements over a stretch of railway track and for providing indications at said remote control location of the condition of said governing device and of traffic conditions in approach to said device; a first control relay, a signal control relay having a low and a high resistance energizing path, and pole changing means responsive to traffic conditions in approach to said device, all located at the location of said device; a biased marginal relay, a second biased relay and a traffic control lever at said control location; said traffic control lever having first, second and third positions; a pair of control conductors extending between said two locations, means controlled in part by said lever and said pole changing means for at times supplying energy from said device location to said first con-

trol relay, said biased marginal relay and said second biased relay over said control conductors; said last mentioned means being effective, in accordance with traffic conditions in approach to said device, to cause either said first control relay and said biased marginal relay or said first control relay and said second biased relay to be picked up; means controlled by said lever and said first control relay for at other times supplying energy from said control location to said biased marginal relay and said signal control relay over said control conductors and effective when the stretch in approach to said device is occupied to supply energy to a circuit including said low resistance energizing path so that both said signal control relay and said biased marginal relay will be picked up but effective when said stretch in approach to said device is unoccupied to supply energy to a circuit including said high resistance energizing path so that the signal control relay will be picked up but said biased marginal relay will be released; means for governing the operation of said device and controlled by said signal control relay, approach indication means at said control location controlled by said biased marginal relay; means for indicating the condition of said device jointly controlled by said biased marginal relay, said second biased relay and said lever; and means jointly controlled by said biased marginal relay, said second biased relay and said lever for preventing said lever from moving beyond said second position when it is in said third position.

3. In an arrangement for controlling from a remote control location a device governing traffic movements over a stretch of railway track and for providing indications at said remote control location of the condition of said device and of traffic conditions in approach to said device, a first control relay, a signal control relay and an approach relay located at the location of said device, said signal control relay being provided with high and low resistance energizing paths, said approach relay being responsive to traffic conditions in approach to said device, pole changing means controlled by said approach relay; a biased marginal relay and a second biased relay located at said control location; a traffic control lever having first, second and third positions and located at said control location; a pair of control conductors extending between said two locations, means controlled by said pole changing means for supplying energy from said device location to said first control relay, said biased marginal relay and said second biased relay through said control conductors when said first control relay is picked up and said lever is in said first or second position; said last mentioned means being effective in accordance with the condition of said pole changing means to cause either said first control relay and said biased marginal relay or said first control relay and said second biased relay to be picked up; means controlled by said approach relay and effective when said lever is in its third position and said first control relay is deenergized for at other times supplying energy from said control location to said biased marginal relay and said signal control relay through said control conductors; said last mentioned means being effective in accordance with the condition of said approach relay to include said high or said low resistance energizing path for said signal control relay in series with said biased marginal relay and the parts being so proportioned that, when the biased marginal relay is in series with said high resistance path, said signal control relay will be picked up and said biased marginal relay will be released but, when the biased marginal relay is in series with said low resistance path, both said signal control relay and said biased marginal relay will be picked up; means governing the operation of said device and controlled by said signal control relay, approach indication means located at said control location and energized when said biased marginal relay is picked up, means located at said control location for

indicating the condition of said device and energized when said lever is in said first or second position and either said biased marginal relay or said second biased relay is picked up, lever locking means effective when deenergized for preventing said lever from moving beyond its second position when it is in said third position and means effective when either said biased marginal relay or said second biased relay is picked up and said lever is in said second position for energizing said lever locking means.

4. In apparatus for controlling a railway wayside signal located adjacent a stretch of railway track, a traffic control lever having first and second positions, a biased marginal relay, a second biased relay, first and second control relays, a stick relay, means controlled by said stick relay and said second control relay for supplying energy to said first control relay; means controlled by said stick relay, said first control relay, traffic conditions in approach to said signal and said lever for supplying energy to said first control relay, said biased marginal relay and said second biased relay in such manner that either said first control relay and said biased marginal relay or said first control relay and said second biased relay will be coincidentally picked up; indication means for indicating the condition of said signal and controlled jointly by said biased marginal relay, said second biased relay and said lever; a second indication means controlled by said biased marginal relay for indicating the traffic conditions in approach to said signal, a signal control relay provided with a low resistance energizing path and a high resistance energizing path; means jointly controlled by said first control relay, said lever and traffic conditions in approach to said signal for picking up said biased marginal relay and said signal control relay through its low resistance path; means jointly controlled by said first control relay, said lever and traffic conditions in approach to said signal for supplying energy to said biased marginal relay and said signal control relay through said high resistance energizing path; said biased marginal relay having characteristics such that it will be released when energized in series with the high resistance energizing path for said signal control relay, means controlled by said first control relay and said signal control relay for energizing said second control relay; means jointly controlled by said signal control relay, said second control relay and traffic conditions in approach to said signal for energizing said stick relay; a stick circuit for said stick relay controlled by said signal control relay, and means for determining the condition of said signal and controlled by said signal control relay.

5. In apparatus for remotely controlling a signal situated at a signal location adjacent a stretch of railway track, a traffic control lever having first, second and third positions and situated at a control location; a biased approach indication relay of the marginal type and a biased signal indication relay located at said control location; first and second control relays and a stick relay located at the signal location; a pair of control conductors extending from the control location to the signal location, an approach relay energized when and only when a portion of said stretch of railway track in approach to said signal is vacant, means effective when said stick relay is energized and said second control relay is deenergized for supplying energy to said first control relay; means effective when said stick relay is energized, said approach relay is energized, said first control relay is energized and said lever is in said first or second position for supplying energy of one polarity to said first control relay, said approach indication relay and said signal indication relay connected in series and being respectively responsive to energy of opposite polarity so that said first control relay and said signal indication relay will be picked up and said approach indication relay will be released; means effective when said stick relay is energized, said approach relay is deenergized, said first control relay is energized and said lever is in said first

or second position for supplying energy of opposite polarity to said first control relay, said approach indication relay and said signal indication relay connected in series so that said first control relay and said approach indication relay are picked up and said signal indication relay is released; signal indication means at said control location for indicating that said signal is displaying its stop aspect; a first means effective when said signal indication relay is picked up and said lever is in its first or second position for energizing said signal indication means, a second means effective when said approach indication relay is picked up and said lever is in said first or second position for energizing said signal indication means; approach indication means for indicating that said portion of said stretch in approach to said signal is occupied, means effective when said approach indication relay is picked up for energizing said approach indication means; lever locking means for preventing said lever from being moved beyond said second position when said lever is in said third position and said lever locking means is deenergized, means effective when said lever is in said second position and either said approach indication relay or said signal indication relay is picked up for energizing said lever locking means, a signal control relay having a low resistance energizing path and a high resistance energizing path and located at said signal location; means effective when said lever is in said third position, said first control relay is deenergized and said approach relay is deenergized for supplying energy to said approach indication relay and said signal control relay through its low resistance energizing path so that both said relays will be picked up; means effective when said lever is in said third position, said first control relay is deenergized, and said approach relay is energized for supplying energy to said approach indication relay and said signal control relay through its high resistance path so that said signal control relay will be picked up but said approach indication relay will be released; means effective when said first control relay or said signal control relay is energized for energizing said second control relay; means effective when said signal control relay is deenergized, said second control relay is deenergized and said approach relay is energized for energizing said stick relay; a stick circuit for said stick relay closed when said signal control relay is deenergized, and means including said signal control relay for controlling said signal.

6. In apparatus for remotely controlling a railway wayside signal situated at a signal location adjacent a stretch of railway track, a traffic control lever having first, second and third positions and situated at a control location, a biased approach indication relay of the marginal type and a biased signal indication relay both situated at said control location and being respectively responsive to energy of opposite polarity, first and second control relays and a stick relay situated at the location of said signal, a pair of control conductors extending from the control location to the signal location, an approach relay, means effective when and only when a portion of said stretch of railway track in approach to said signal is vacant for energizing said approach relay, means including a front contact of said stick relay and a back contact of said second control relay for supplying energy to said first control relay; means including a front contact of said stick relay, a front contact of said approach relay, a front contact of said first control relay and a contact closed when said lever is in said first or second position for supplying energy of one polarity to said first control relay, said approach indication relay and said signal indication relay connected in series so that said first control relay and said signal indication relay will be picked up and said approach indication relay will be released; means including a front contact of said stick relay, a back contact of said approach relay, a front contact of said first control relay and a contact closed when said lever is in said first or second position for supplying energy of opposite polarity to said

first control relay, said approach indication relay and said signal indication relay connected in series so that said first control relay and said approach indication relay are picked up and said signal indication relay is released; signal indication means for indicating, when energized, that said signal is displaying its stop aspect, a first means including a front contact of said signal indication relay and a contact closed when said lever is in said first or second position for energizing said signal indication means, a second means including a front contact of said approach indication relay and a contact closed when said lever is in said first or second position for energizing said signal indication means, approach indication means for indicating, when energized, that said portion of said stretch in approach to said signal is occupied, means including a front contact of said approach indication relay for energizing said approach indication means, lever locking means for preventing said lever from being moved beyond said second position when said lever is in said third position and said lever locking means is deenergized, a first means including a contact closed when said lever is in said second position and a front contact of said approach indication relay for energizing said lever locking means, a second means including a contact closed when said lever is in said second position and a front contact of said signal indication relay for energizing said lever locking means, a signal control relay having a low resistance energizing path and a high resistance energizing path; means including a contact closed when said lever is in said third position, a contact closed when said first control relay is de-
